UNITED STATES PATENT OFFICE.

LEON JARUSZ, OF CHICAGO, ILLINOIS.

SCRUBBING-MACHINE.

1,393,133.

Specification of Letters Patent. Patented Oct. 11, 1921.

Application filed October 6, 1919. Serial No. 328,674.

To all whom it may concern:

Be it known that I, LEON JARUSZ, a citizen of the United States, residing at Chicago, in the county of Cook and State of Illinois, 5 have invented new and useful Improvements in Scrubbing-Machines, of which the following is a specification.

This invention has relation to floor cleaning machinery, and refers particularly to a 10 portable hand-operated floor scrubbing machine.

The general object of my invention is the provision of a simple and inexpensive structure of the kind referred to. More particularly I aim to provide a combination, in such machine, of a scrubbing element with a squeegee device. A further object is to provide a reservoir within the machine and capable of holding a cleaning fluid, and of 15 means for gradually releasing the said fluid for scrubbing purposes. Another object is to provide means for drawing the cleaning fluid back into the machine at the time the squeegee is drawn over the floor in order to 20 finish the cleaning operation. Finally I aim to provide various novel and advantageous features which will be hereinafter fully pointed out and illustrated in the appended drawings, of which:

30 Figure 1 is a side-elevation in section of a machine embodying the invention,

Fig. 2 is a fragmentary view looking down upon the machine of Fig. 1,

Fig. 3 illustrates a modified form of machine, and

Fig. 4 shows a further modification of the preceding structure.

Referring in the first instance to Figs. 1 and 2, attention is invited to the three main 40 features of the machine, namely a handle 1, a detachable scrubbing brush 2 and a squeegee element 3. The said handle is preferably cylindrical in shape and hollow, having a lower chamber 1^a, which forms a reservoir 45 for the cleaning fluid and which terminates at the bottom in a valve 4. The said valve is held yieldingly closed by a spring 5, and it is manually operable through the medium of a lever 6 and a pull-rod 7. It is readily 50 seen that the operator is able to regulate the feeding of cleaning fluid to the brush, as required, by pulling the rod 7, and that the spring 5 will re-seat the said valve the moment the pull-rod is released.

55 Through the chamber 1^a extends a tube 8, which operatively connects the upper han-

dle-chamber 1^b with the squeegee mechanism in the following manner. The tube terminates at the bottom in a channel 9, which by a flexible tube 10 communicates 60 with a passage 11 of the squeegee. In the said passage is seated a spring-held valve 12, which normally closes an outlet 13. In the upper chamber is fitted a piston 15, having a rod 16 extending through the top of 65 the handle, and terminating in a hand-pull 17. In the partition between the upper and lower chambers is placed a spring-held and downwardly opening valve 18.

After the scrubbing operation is completed the machine is turned until the squeegee rests upon the floor, and the machine is then drawn toward the operator in order to remove the fluid. Now it is observed, see 70 Fig. 2, that the squeegee and its support are formed into an obtuse angle, and this is done in order to direct the fluid to the squeegee outlet 13, which latter terminates directly inside the apex of the said angle. During 75 the said movement of the squeegee over the floor the operator commences to pull on the draw-pull 17, thereby creating a suction through the tube 8 and the passages 9, 10, 11 and 13, which suction in turn causes the valve 12 to open and permits the accumulating 80 fluid at the apex to rise into the upper chamber 1^b. Having completed the suction stroke, the operator reverses the piston movement by pushing on the hand-pull 17, and instantly the pressure closes the valve 12, aided 85 by its spring, while simultaneously the valve 18 is forced open, thereby permitting the fluid to escape into the reservoir 1^a, the displaced air of which escapes through an air-vent 1^c. 95

When it is desired to clean out the machine the valve 4 is opened, and the said valve may be held in open position by bringing a notch of the rod 7 into engagement with an edge 1^d of the handle. The operator 100 now places a finger on the air-vent 1^c, whereupon he moves the piston back and forth, and the fluid is gradually expelled. The lower portion of the machine is now placed 105 in a body of clean water, or other suitable agency, and the pumping operation is continued until sufficient fluid has been circulated through the machine to thoroughly clean it out. The valve 4 is then re-seated, whereupon the lower portion of the machine 110 may be dipped into floor-cleaning fluid, and it is then re-filled by drawing the piston

back to the top, and returning it to its initial position.

The most important elements of the machine are the valves, and the problem is to provide valves which are not easily clogged up, and which are readily accessible when they do become clogged with dirt. In public places, where a machine of this character is much needed, the floors usually become littered with rubbish, which, of course, is removed by sweeping or otherwise, but a quantity of small particles remain for the machine to remove. In Figs. 3 and 4 I have illustrated modified structures designed with a view of minimizing valve troubles.

The structure of Fig. 3 comprises a handle 20, provided with an upper and a lower chamber 20^a and 20^b, respectively and the said chambers are in permanent communication by means of a passage 20^c. In fact it is not essential that there should be two chambers, and the partition 20^d is merely placed in order to confine the fluid, as nearly as possible, within the lower portion of the machine, so as to keep the said fluid away from the pump. The latter comprises a piston 21, having a stem 22 and an operating handle 23. In the piston is set a spring-held valve 21^a, which opens on the down-stroke of the piston. The machine handle terminates at the bottom in a head 24 having a passage 24^a, which is controlled by a valve 25, and the said valve is held normally closed by a spring 26, and it is manually operable through the medium of a pull-rod 27 having a finger-piece 27^a. The said finger-piece is made with a stem 27^b, which is slidably fitted in a lug 20^e of the machine handle 20, and it is observed that the said stem covers a small air-vent 20^f. For the purpose of feeding fluid to the scrubbing brush it is only necessary to raise the finger-piece slightly, thereby opening the valve 25 and also uncovering the vent 20^f. An additional movement of the stem 27^b again closes the vent and further opens the said valve, and this is the proper adjustment for cleaning out the machine, as has hereinbefore been described.

Adjacent to the passage 24^a is a second passage 24^b, which opens into a valve chamber 24^c, and terminates in an orifice 24^d in close proximity to a squeegee 29. The inner edge of the said orifice forms a seat for a valve-member 30, and the latter is held normally seated through the medium of a spring 31. A screw cap 32, or its equivalent, closes an entrance to the said valve-chamber. In the manner hereinbefore described the fluid is rubbed off the floor and drawn into the squeegee apex, and it is then drawn back into the reservoir 20^b through the valve-chamber 24^c. The member 30 is preferably made of soft resilient material, in order that it may seat tightly even though

some particle should lodge on the valve seat. But if a leakage does occur, it is required only to examine the valve from the outside and to push the ball back a trifle, and the obstruction is readily removed. By removing the screw-cap 32 the ball and spring can be taken out and the whole valve-structure cleaned, without disturbing the rest of the machine.

In the device illustrated in Fig. 4 the valve chamber 35^a, of the head 35, has been enlarged, so as to form a sediment reservoir, which is closed by a plate 36, and the latter in turn pivotally supports a spring-held valve 37. The said valve is shown cup-shaped, it may be made of rubber or other soft resilient material, and it fits over a crowned valve-seat 35^b. A leakage at the said valve is quickly cured from the outside, and the entire valve is readily removed with the plate 36 for more extensive cleaning. In the chamber 35^a, and above the said valve, is placed a fine wire-screen 38, which prevents solids from rising into the handle 40 through a passage 35^c and a tube 39, and the said screen may be removed at any time when the plate 36 is detached. The opposite end of the passage 35^c is normally closed by a spring-held and manually operated valve 41.

Upon examination it is observed that the machine handles of the structures illustrated in Figs. 1 and 4 are pivotally connected with the scrubbing heads. In Fig. 3, on the other hand, the parts are shown rigidly combined. My aim is to provide structures of either type to suit trades and operating conditions. I may also effect further modifications in the various component elements of my invention, as demanded by operating conditions, without departing from the general principles of the invention, as set forth in the following claims.

I claim:

1. A hollow fluid holding handle, a scrubbing head pivoted on one end of said handle, a flexible conduit operatively connecting the interior of said handle and head, manually operated means for permitting fluid to drain out of the handle, and means operated by a hand grip projecting from the opposite end of the handle for returning the fluid through said flexible conduit to the handle.
2. A hollow stem having a lower fluid chamber and an upper pump chamber, a scrubbing head at one end of the stem, said stem having an outlet and an inlet passage to the said fluid chamber, a device having a handle centrally placed on the stem for opening the said outlet, a spring-held inlet valve closing the said inlet passage, and a manually operated piston slidable in the upper chamber for returning the fluid through the said inlet valve and passage.
3. In a scrubbing machine, a handle hav-

ing a fluid-reservoir, a scrubbing brush, a squeegee, manually operated devices for feeding fluid to the said brush, a pump in the said handle, and a valve operating on 5 the suction stroke of the said pump to open a passage for the fluid to return to the said reservoir.

4. In a floor scrubbing machine, a tubular fluid holding stem, a head mounted on one 10 end of said stem, a brush detachably fixed on said head, manually controlled means for feeding fluid from the stem to said brush, a V-shaped squeegee on the head, said head having a passage the inlet of 15 which is positioned within the apex of said squeegee and which leads into said stem, a spring held valve closing said inlet, a de-

vice within the stem for returning fluid from the floor to the stem, and a grip rod projecting through the other end of the stem 20 for operating said device.

5. In a floor scrubbing machine, a fluid holding stem, a head on one end of said stem, a brush detachably mounted on said head, a squeegee on the head, the operating 25 faces of said brush and squeegee forming an obtuse angle in order that one of said members may clear the floor while the other member is in operation, means for feeding fluid from said stem to said brush, and means 30 for returning said fluid from the floor to the stem.

LEON JARUSZ.
